UNITED STATES PATENT OFFICE

CLIFTON W. NIXON, OF NEW YORK, N. Y.

COIN-CONTROLLED MECHANISM

Application filed June 7, 1926. Serial No. 114,112.

My present invention relates to coin-controlled mechanism, and the same has for its main object to provide an improved construction of this character for use in connection with vending machines, change-making machines and similar apparatus, and further to provide an improved construction of this character for use generally in places and capacities where it is desirable to control the 10 operation of a machine or apparatus through the medium of a deposited coin.

An object of my invention is the provision of a coin-controlled mechanism in the form of a compact operative unit which will embody certain desired features of simplicity, efficiency and convenience, and which will be economical in manufacture.

A further object of my invention is the provision of a coin-controlled mechanism of this 20 character, constructed and arranged to embody a coin-testing device for rejecting slugs and spurious coins.

Other objects of my invention are: to provide a coin-controlled mechanism including 25 an operating shaft provided with one or more coin slots and so constructed and arranged that it is capable of serving as the means by which directly to impart movement to or to actuate the machine or apparatus with which 30 the coin-controlled mechanism is associated; to provide a mechanism of this character including a coin-carrier having a coin-seat and a pivoted element or slide, said mechanism further including locking means associated 35 with the coin-carrier and arranged to be released or unlocked by the pivoted element when a coin is lodged in the coin-seat; and to provide a mechanism of this character in 40 which the operating shaft and coin-carrier have an operative connection therebetween to cause the coin-carrier to move with the operating shaft and to cause the operating shaft to be locked against movement when the coin-carrier is locked by the locking 45 means.

With the foregoing objects and others in view, my invention consists in the details of construction and in the arrangement and combination of parts hereinafter described and 50 more particularly pointed out in the annexed

claims, reference being had to the accompanying drawings, in which:

Fig. 1 represents a side elevational view showing a coin-controlled mechanism made in accordance with the present invention; 55

Fig. 2 is a top plan view of the same;

Fig. 3 is an elevation of the operative end of the mechanism, this view being taken on the line 3-3 of Fig. 1;

Fig. 4 is a vertical section taken on the line 60 4-4 of Fig. 1;

Fig. 5 is a vertical section taken on the line 5-5 of Fig. 1;

Fig. 6 is a horizontal section taken on the line 6-6 of Fig. 1; 65

Fig. 7 is a horizontal section taken on the line 7-7 of Fig. 1; and

Fig. 8 represents a sectional detail taken on the line 8-8 of Fig. 1.

The preferred embodiment of my invention, as illustrated in the accompanying drawings, comprises a frame structure composed of a base 9 from which rises a side wall 10 made with a vertically extending upright or pillar 11 at the operating end of the device and with a vertically extending upright or pillar 12 at the rear end of the device. The side wall 10, intermediate its length, has a portion 13 offset inwardly over the base for a purpose hereinafter to be explained. The 70 uprights 11 and 12 are made respectively with lateral portions 14 and 15 which overhang the base and in which an operating shaft 16 is mounted to have both reciprocating and turning movement. The parts so far described may, if desired, be cast as one piece. Said shaft 16 is provided with a suitable knob 17 whereby to be turned and to be thrust-in; and it is also provided in the present embodiment with two transverse coin-slots 18 and 18', which slots intersect each other at the center of the shaft. Arranged upon the lateral portion 14 is a coin-deposit chute 19 suitably beveled downwardly and forwardly at 19' so that a coin as 20, when resting upon the shaft 16, may protrude therefrom as shown in Fig. 1. 85

Arranged upon the base 9 for reciprocating movement is a coin-carrier which is composed of a backing slide 21 and a pivoted 90

element or slide 22. The backing slide 21 has sliding contact with the inner face of the offset wall portion 13, its lower edge being slidably fitted in a groove 23 in the base and its upper edge being slidably fitted in a groove 24 provided in an overhanging horizontal bar 25 which is secured to the offset wall portion 13. Said backing slide, at its rear end, has a laterally offset head 26 from which is suitably spaced the rear end of the slide 22 which is pivoted at 27 upon said backing slide 21. The head 26 and confronting end of the slide 22 are suitably vertically slotted at 28 and 29 respectively, in order to provide a coin-seat, the wall defining the slot 29 being suitably curved at 30 in order better to maintain the coin in its seat. The pivoted slide 22 has a lost motion movement upon a stud 31 fixed to the backing slide 21 and projecting through an opening 32 in said slide 22. Mounted for rocking movement upon the stud 31 alongside the slide 22 is a two-part pawl 33 which cooperates with a two-part rack-bar 34 fixed upon the base, the teeth of one part of the rack-bar projecting in a direction opposite to the inclination of the teeth in the other part thereof, the two sets of oppositely inclined teeth being separated by an upwardly projecting cam-like landing 35.

The forward pawl-point or portion 36 is adapted to slide from and to an elevated position on the landing 35 and also to interlock with the rearwardly directed rack-teeth 37. Upon a stud 39, projecting from the backing slide 21, a spring 38 is looped and secured so as to have a short arm 40 exerting downward pressure upon a pin 41 on the pivoted slide 22, and a long arm 42 exerting downward pressure upon a pin 43 projecting from the rearward pawl-point or portion 44, which is adapted to interlock with the forwardly directed rack-teeth 45. The pin 41 by which the forward portion of the slide 22 is supported upon the forward portion of the pawl constituting the pawl-point 36, is so situated that when the pawl-point 36 rests at a predetermined elevation or seat on the cam-like landing 35 as shown in Fig. 1, the said slide 22 will be maintained in such position relatively to the head 26 that a coin as 20, on entering the coin-seat, will fall to and be caught by the curved portion 30 thereof.

Now the arms 40 and 42 are so shaped and arranged that the force exerted by the arm 40 upon the pin 41 and hence upon that portion of the pawl constituting pawl-point 36 is in excess of the force exerted by the arm 42 upon the pin 43. This insures to the pawl a tendency at all times to swing into that position in which the pawl-point 36 will interlock with the rack-teeth 37, except when there is a coin lodged in the coin-seat, in which case the force of the spring arm 40 cannot influence the swinging of the pawl because

the downward pivoting of the slide 22 is obstructed by the coin within the coin-seat. Under this arrangement, initial movement forwardly of the coin-carrier without a coin in the coin-seat results in automatically swinging the pawl so that its pawl-point 36 will follow the declivity of the cam-like landing 35 and interlock with one of the rack-teeth 37, thereby holding the coin-carrier against further advancing movement but permitting retiring movement thereof since the pawl-point 44 will be raised clear of the rack-teeth 45 when the pawl has been swung into that position where the pawl-point 36 is interlocked with one of the rack-teeth 37.

When the coin-carrier is advanced with a coin reposing in the coin-seat the slide 22 is held by such coin against downward pivoting, and since under this condition the arm 40 has no influence upon the pawl the arm 42 becomes effective to maintain the pawl in that position where the pawl-point 36 will escape interlocking action with the rack-teeth 37 while the pawl-point 44 will click over the rack-teeth 45. During the time a coin is lodged in the coin-seat, the coin-carrier cannot be retired since the pawl-point 44 will interlock with one of the rack-teeth 45. Means for lifting up the forward portion of the slide 22 so that the sustained coin will be released to fall from its coin-seat consists in providing said slide with a projecting pin 46 arranged to engage and slide upwardly upon the high point of the cam-like landing 35 at the termination of the advancing stroke of the coin-carrier.

The coin-carrier is operatively connected with the operating shaft to be reciprocated therewith by means of a connecting bar 47 which is mounted intermediate its length upon a stud 48 fixed to the rear upright 12. The lower end of bar 47 has a pin 49 which works in a slot 50 in the backing slide 21, while the upper end of said bar has a cam-like pin 51 extending into the circumferential groove 43 in the operating shaft 16 and adapted to be engaged by a suitable shoulder or abutment as 52 for determining the extent of turning movement of said shaft. By this arrangement the coin-carrier will be moved forward when the operating shaft is thrust in; and conversely the coin-carrier will be retired when the operating shaft is thrust out, an operation which is accomplished by a repositioning spring 54 connected for the purpose between the upright 14 and pin 51 on the connecting rod 47. In this connection it may be remarked that the coin-deposit chute 19 affords a convenient finger-hold when thrusting the operating shaft which is accomplished by pressing the palm of the hand on the knob 17 while engaging a finger over the chute 19.

By turning the knob 17, either coin-slot 18 or 18' may be brought into register with

the coin-chute 19 so that the deposited coin as 20 will fall through the shaft and into an underneath chute 55. It should be noted here that the coin-slots 18 and 18' are sized to the particular denomination of coin which is to be employed in operating the machine; that is to say, said coin-slots are made just large enough to permit the particular denomination of coin to fall therethrough so that a slug or a spurious coin having either a diameter or thickness slightly greater than a genuine coin cannot be passed through said coin-slots into chute 55.

From the underneath chute 55, the coin rolls into a balanced chute 56 provided at its forward end with oppositely projecting ears 57, each terminating in a pivot pin 58 suitably journaled in a U-shaped member 59 secured upon the horizontal bar 25. Projecting forwardly from the ears 57 so as to be located on opposite sides of the underneath chute 55 are weights 60 for balancing the chute, one of the weights being adjustable on an axis so as to suitably vary the adjustment of the chute. Said chute is balanced and adjusted to incline downwardly for the delivery of its coin into a lead-in chute 61 through which the coin falls for lodgment in the coin-seat of the coin-carrier. The coin-chute is so balanced that when a normal coin runs downwardly thereon, it will sink to a position to register a rear bottom lip 62 with the top edge of the lead-in chute so that the rolling coin guided by a side flange 63 on the chute will roll directly into the lead-in chute whose mouth is suitably beveled and surrounded at the rear by a flange 64. Supported upon the horizontal bar 25 is a switch-arm 65 provided with a finger 66 which curves laterally over the flange 63 of the chute and also over the line of the mouth of the lead-in chute as best illustrated in Fig. 6. When a normal coin rolls down the balanced chute, it rolls under the switch-finger since the chute sinks sufficiently for this purpose; but if the rolling coin proves to be lighter than a normal coin the chute will not sink sufficiently to bring the coin below the finger with the result that the finger will divert the coin into a by-pass chute 67 which drops the coin through a slot 68 in the base. Referring to Fig. 6 it will be seen that the bottom-lip 62 curves laterally to clear the curving side 69 of the lead-in chute. Now if the rolling coin proves to be a trifle heavier than a normal coin, the balanced chute will be sunk to a level in which the curved wall 69 will intercept the rolling coin and serve as a switch by which to roll it over the lip 62 and into the by-pass chute 67. Thus it will be seen that the balanced chute will function to bring a too-light coin into engagement with the switch-finger and will also function to bring a too-heavy coin into engagement with the curved wall of the lead-in chute, whereby either a too-light

coin or a too-heavy coin will be diverted into the by-pass chute.

When there is no coin in the coin-seat of the coin-carrier, the locking means associated with the carrier automatically functions to prevent advancing movement of the carrier with the result that the operating shaft cannot be thrust in. When, however, a deposited coin has successfully passed the tests to which it is subjected by the balanced chute and is lodged in the coin-seat, the pawl of the locking mechanism, influenced only by the spring arm 42, is held so that the point 36 clears the rack-teeth 37 to allow the thrust-in movement of the operating shaft and the consequent advancement of the coin-carrier. During the advancement of the coin-carrier, the pawl-point 44 cooperates with the rack-teeth 45 to prevent any retiring movement until the pivoted slide 22 is tripped upwardly by the engagement of the pin 46 with the high point of the cam-like landing 35—an operation which results in the release of the coin which drops through the slots 68 in the base and thence into a cash box (not shown). The coin having been released, the spring arm 40 thereupon functions to reverse the position of the pawl lifting the pawl-point 44 from the rack-teeth 45 so that the spring 54 can reposition the operating lever and cause the retirement of the coin-carrier for the next operation.

A stop-pin 70 which projects from the rear upright 12 in position to engage the connecting bar 47, serves as the means for limiting the retiring movement of the coin-carrier at the exact point where the coin may fall from the lead-in chute 61 into the coin-seat of the coin-carrier.

Arranged at the front end of the device upon a bracket 71 depending from the horizontal bar 25 is a suitable register 72 having an operating arm 73 which is connected through a link 74 with the pawl supporting-stud 31. By this arrangement register 72 is operated to record a sale each time the coin-carrier is advanced.

The present coin-controlled mechanism may be utilized in a machine having facilities for vending two different classes or kinds of goods selling for the same price. To this end the operating shaft 16 may be equipped with a suitable arm 75 with which a suitable index and dial (not shown) may be associated for operation to indicate the two classes or kinds of goods on sale. The thrust-in movement of the operating shaft 16 may be used to effect the operation of the machine with which the present device is associated. To this end, the operating shaft is equipped with a fixed pin 76 which may be engaged either with a contact lever 77 or a contact lever 78 accordingly as the operating shaft is turned. The said contact levers 77 and 78 may represent the means through which to effect the delivery of a choice of two kinds of merchandise.

While I have illustrated and described the preferred form of construction for carrying my objects into effect, this is capable of variation and modification without departure from the spirit of the invention, I therefore, do not wish to be limited to the details of construction herein set forth, but desire to avail myself of such variation and modification as come within the scope of the appended claims.

Having thus described my invention, what I claim and desire to secure by Letters Patent is:

1. Coin-controlled mechanism including an operating shaft having a coin passageway; a coin-carrier having a coin-seat; a chute for conducting the coin from said passageway to said coin-seat; locking means for the coin-carrier arranged to be controlled thereby and to be held in released position upon the lodgment of a coin in said coin-seat; and an operative connection between said operating shaft and said carrier.

2. Coin-controlled mechanism including two slides jointly comprising means adapted to sustain a coin, one of said slides being pivoted to the other; means for reciprocating said slides; and locking means associated with said slides by which automatically to lock them against movement, said pivoted slide being adapted through the engagement therewith of a sustained coin to prevent said locking means from assuming a locking position.

3. Coin-controlled mechanism including two movable slides and means for moving them, said slides jointly comprising means for the lodgment of a coin, one of said slides being pivoted to the other and adapted to be sustained by a lodged coin against pivoting movement; a pawl normally arranged to be swung by the pivoting movement of said pivoted slide; a rack adapted to be engaged by said pawl for holding said slides against movement; and means impelling the pivoting movement of said pivoted slide to provide for the engagement of said pawl with said rack when said pivoted slide is unsustained by a coin.

4. Coin-controlled mechanism including an operating shaft; a coin-carrier having operative connection with said shaft; a coin-engaging slide pivoted to said coin-carrier and tensioned to normally swing in one direction; and pawl and rack mechanism adapted for engagement to prevent the operation of said coin-carrier, said pawl being arranged to provide a support for said tensioned slide and to be moved thereby into engagement with said rack.

5. Coin-controlled mechanism including an operating shaft; a coin-carrier having operative connection with said shaft; a coin-engaging slide pivoted to said coin-carrier and adapted to be sustained against downward movement by an engaged coin; pawl and rack

mechanism adapted for engagement to prevent the operation of said coin-carrier, said pawl being pivoted to said coin-carrier and constituting a support to limit the downward movement of said slide; and spring means forcing said slide and pawl into impingement and arranged to cause said pawl to engage its rack when said slide is not sustained by a coin and further to cause said pawl to escape said rack when said slide is sustained by a coin.

6. Coin-controlled mechanism including an operating shaft; a coin-carrier having operative connection with said shaft; a coin-engaging slide pivoted to said coin-carrier and adapted to be sustained against downward movement by an engaged coin; pawl and rack mechanism adapted for engagement to prevent the operation of said coin-carrier, said pawl being pivoted to said coin-carrier and constituting a support to limit the downward movement of said slide; a cam landing adjoining said rack for positioning said pawl and slide; and spring means forcing said slide and pawl into impingement and arranged to cause said pawl to engage its rack when said slide is unsustained by a coin and further to cause said pawl to escape said rack when said slide is sustained by a coin.

7. In a coin-controlled mechanism, the combination with a base and an operating element, of a coin-carrier slideable along said base and connected with said operating element to be operated thereby; a coin-engaging slide pivoted to said coin-carrier and adapted to be sustained by an engaged coin; and pawl and rack mechanism between said coin-carrier and base adapted for engagement to prevent the operation of said coin-carrier, said mechanism being arranged to be controlled by said slide and to be held out of engagement when said slide is sustained by an engaged coin.

8. In a coin-controlled mechanism, the combination with a rack, of a movable coin-carrier; a coin-engaging slide pivoted to said coin-carrier and adapted to be sustained by an engaged coin; a pawl carried by said coin-carrier and adapted to be engaged with said rack to prevent the operation of said coin-carrier; and spring means acting on said slide and pawl to force them into impinging relation, said spring means being arranged to cause said slide, when unsustained by a coin, to force said pawl into engagement with said rack.

9. In a coin-controlled mechanism, the combination with a rack and a cam landing, of a movable coin-carrier and means for moving the same; a coin-engaging slide pivoted to said coin-carrier and adapted to be sustained by an engaged coin; a pawl carried by said coin-carrier and adapted to be engaged with said rack to prevent the operation of said coin-carrier, said pawl being arranged

to constitute a support for said slide to be controlled thereby and to be held out of engagement with said rack when said slide is sustained by an engaged coin and said pawl being further arranged for cooperation with said cam landing to adjust said slide to a position in which it can be engaged and sustained by a coin.

10. In a coin-controlled mechanism, a coin-carrier and means for moving it, said coin-carrier having a coin-seat and provided with a pivoted element arranged to be sustained against pivoting movement in one direction by a coin lodged in said coin-seat; locking means for the coin-carrier arranged to be controlled by the pivoting movement of said pivoted element and to be held in released position when said pivoted element is sustained by a lodged coin; and means for tripping said pivoted element in the opposite direction to free the lodged coin.

11. In combination, a coin-carrier mounted for advancing and retiring movement and including a coin-seat and a pivoted element arranged to be sustained by a coin lodged in said coin-seat; means for advancing and retiring said coin-carrier; a two-part pawl constituting a support for said pivoted element until the latter is sustained by a lodged coin; a two-part rack for said pawl; and a spring element associated with said coin-carrier, pivoted element and pawl to normally maintain said pawl in position with respect to said rack to allow advancing movement and to prevent retiring movement, of said coin-carrier when said pivoted element is sustained by a coin.

12. In combination, a coin-carrier mounted for advancing and retiring movement and including a coin-seat and a pivoted element arranged to be sustained by a coin lodged in said coin-seat; means for advancing and retiring said coin-carrier; a two-part pawl and a cooperating two-part rack, said pawl constituting a support for said pivoted element until the latter is sustained by a lodged coin; spring means associated with said coin-carrier, pivoted element and pawl to maintain said pawl in position with respect to said rack to allow advancing but not retiring, movement of said coin-carrier when said pivoted element is sustained by a coin, and further to operate said pivoted element to prevent advancing but not retiring, movement of said coin-carrier when said pivoted element is supported by said pawl.

13. In a coin-controlled mechanism, the combination with a coin-carrier, of operating means adapted to admit a coin in either one of two positions for passage to said coin-carrier, said operating means comprising a shaft mounted to have both reciprocating and rotary movement and having intersecting coin-slots leading transversely through it from opposite points of its circumference; and con-

necting means between said shaft and coin-carrier adapted to receive and transmit only the reciprocating movement of the former to the latter.

14. In a coin-controlled mechanism, the combination with a coin-carrier, of operating means adapted to admit a coin in either one of two positions for passage to said coin-carrier, said operating means comprising a shaft mounted to have both reciprocating movement and rotary movement and having intersecting coin-slots leading transversely through it from opposite points of its circumference; and an operative connection between said shaft and said coin-carrier comprising a fulcrumed bar having one end thereof pivoted to said coin-carrier, and a pin on the other end of said bar engaging a circumferential groove in said shaft.

In testimony whereof, I have signed my name to this specification.

CLIFTON W. NIXON.
